UNITED STATES PATENT OFFICE.

DOMINICK J. CAMELO, OF TUPPER LAKE, NEW YORK.

DESIGN FOR A GRAVE MARKER.

Application filed April 2, 1928. Serial No. 26,102. Term of patent 7 years.

To all whom it may concern:

Be it known that I, DOMINICK J. CAMELO, a citizen of the United States, and resident of Tupper Lake, in the county of Franklin and State of New York, have invented a new, original, and ornamental Design for a Grave Marker, of which the following is a specification, reference being had to the accompanying drawing, forming part hereof.

I claim:

The ornamental design for a grave marker, as shown.

DOMINICK J. CAMELO.
